LAMP BASE OR SIMILAR ARTICLE

Robert F. Laabs, Haskell, N. J., assignor to Cambridge Lamps, Inc., Newark, N. J., a corporation of New Jersey

Application July 25, 1956, Serial No. 42,382

Term of patent 3½ years

(Cl. D48—19)

The figure is a side perspective view of a lamp base or similar article showing my new design.

The broken lines in the drawing are for illustrative purposes only. The lamp base is symmetrical and has the same appearance when viewed from all four quarters.

I claim:

The ornamental design for a lamp base or similar article, as shown and described.
